SPRING COMPRESSOR

Harry W. Kulp and Martin C. Dellinger,
Lancaster, Pa.

Application October 27, 1932. Serial No. 639,912

5 Claims. (Cl. 29—86.3)

This invention relates to spring compressors of the one hand plier type and is particularly intended for use in compressing the valve springs of automobile internal combustion engines.

The primary objects are to provide in such a tool a construction whereby the opposed faces of the operative jaws will be maintained substantially parallel throughout their range of travel; to provide a very compact construction; to provide an automatic locking means; to so relate the locking means with other portions of the device that said locking means will also serve as guiding means and said other parts will serve to maintain said locking means in a definite path of travel, and to provide said locking means with a release lever disposed between the normal operative handles of the tool, whereby said releasing lever will be readily accessible to operation by the mechanic's finger and at the same time will be out of the way.

In the accompanying drawing:

Figure 1 represents a perspective view of a spring compressor embodying our invention, in closed condition;

Figure 2, a side elevation of said spring compressor in its extreme open position;

Figure 3, a sectional view taken on the line 3—3 of Fig. 1, looking in the direction of the arrows;

Figure 4, a sectional view of the hand lever 4 taken on the line 4—4 of Fig. 2, looking in the direction of the arrows; and

Figure 5, a fragmentary detail view of the lever 6 to show the cam surfaces 14 and 15, the rivet 10 being shown in section, and the adjacent portion of the jaw member 2 being broken away and shown in section to illustrate the relation of the rear edge 2^a of jaw member 2 and the rivet 10 to said cam surfaces 13 and 14 respectively.

Referring now in detail to the drawing, the tool comprises a lower lever or beam having a jaw portion 1 and a handle portion 3, a lever 6 having its lower end pivotally connected by rivet 8 to the forward portion of the jaw portion 1 immediately to the rear of the bifurcation thereof and threaded through the rear portion of the upper jaw member 2, to have sliding engagement therewith, and cross levers 5 pivotally connected to the forward end portion of the jaw member 2 by a rivet 7 immediately to the rear of the bifurcation in the forward portion of said member 2, and having their lower ends arcuately slotted as at 11 to receive the

rivet 9 passing through the rear portion of the jaw portion 1 for slidable pivotal connection to said portion 1, said levers 5 and 6 crossing each other and being pivotally connected together by the rivet pin 12 at their central crossing point. 69

A handle 4 is to be fitted around the upper end of lever 6 and secured thereto in any convenient or usual manner, as by a rivet 4^a.

The jaw member or beam 2 will be of channel form and will have its rear lower corners 65 continue down beyond the face of the cam 14 and is provided in the portions depending below said cam surface with registering perforations to receive a fastening rivet 10, which in the operative movement of the lever 6, serves to 70 hold the rear edge 2^a of the web or bridge of said member 2 in freely sliding contact with the cam surface 13, while itself being held in freely sliding contact with the cam surface 14, substantially throughout the range of movement of the lever 6 with relation to the beam 75 1—3.

The arcuate slots 11 in the levers 5 are formed to coincide with the path of movement of the lower end of levers 5 as the said levers 80 5 move rearwardly as a whole in accordance with the movement of the lever 6 about the pivot 8 and simultaneously turn about the pivot 12, in accordance with the movement of said lever 6 as the jaw portions 1 and 2 are caused 85 to move toward or from each other.

A preferably bifurcated locking lever 15 is mounted so as to straddle the lever 6, being pivotally mounted thereon by the rivet 17 and having its furcations disposed on opposite sides 90 of the lever 6 and at all times extending between said lever and the opposed inner faces of the rear portions of the sides of said channel member 2 and acting as spacing or guiding blocks maintaining the proper centered relation between said lever 6 and the channel form jaw member 2. 95

The forward ends of said furcations will be provided with a plurality of forwardly presented stop faces or serrations 16 and the ends of the furcations forming the lever 15 are brought together to the rear of the pivot 17, being preferably rigidly connected together as by welding as indicated at 18^a and continued in the form of an upwardly curved operating lever 18 having its rear end portion formed with a perforation 19 which receives the loop portion of the bifurcated substantially U-shape spring 20, which straddles and is positioned by the upper 105 end portion of the lever 6 and bears against 110 the rear end portion of the lever 6.

the opposed lower face of the handle 4, so shoving the lever 18 downward and serving to yieldingly force the furcations of lock lever 15 upward against the rear edge of the jaw member 2, so that as the lever 6 is swung about its pivot 8 to move the jaw portions 1 and 2 and the handles 3 and 4 toward each other the cam surfaces 13 and 14 will move slidingly rearwardly through the rear portion of the jaw member 2, and similarly the pivotal point of the lever 15 will be moved rearwardly with relation to the rear edge 2^a of the jaw member 2, so that the furcations of the lever 15 will be progressively withdrawn from between the sides of the member 2 and lever 6 and the spring 20 will cause the lever 18 to be depressed, so that as each pair of locking stops or faces 16 moves past the rear edge 2^a of member 2, the spring 20 will turn the locking lever 15 so that said stops will engage said edge 2^a, locking the parts against reverse movement until the lock is released.

The locking lever 15 has its legs or furcations recessed as at 21 so as to receive, or not to interfere with, the rear ends of the levers 5, as illustrated in Fig. 1. It will be noted that in this relation of the parts the portion of the lever 6 immediately to the rear of and adjacent the cam faces 13 and 14 will be disposed between the rear ends of the levers 5 substantially in rubbing contact therewith.

The respective levers or links 5 are disposed on opposite sides of the lever 6 and have a large area rubbing contact therewith to be properly held and spaced apart thereby, and this construction in association with the interposition of the respective ends of the furcations of the locking lever 15 between the respective sides of the lever 6, and the opposed faces of the corresponding sides of the jaw member 2, and in association with the relationship of the rear portions of the levers 5 and the lever 6 in the final stages of the closing movement of the parts, serves to provide a very sturdy yet freely moving construction which is very thoroughly braced against lateral distortions or "weaving" of the parts in stress.

Preferably all portions of the valve-spring compressor illustrated, with the exception of the rivets and the spring, are made from sheet metal stampings and preferably the lower beam comprising the jaw portion 1 and the handle portion 3, and also the upper jaw member 2 and the handle 4, will be of channel form in cross section.

Preferably also the rear portion of the web of the member 2 will be centrally struck up as at 2^b to provide a guiding channel to receive the edge portion of the lever 6 and center the rear end of the member 2 with relation to said lever 6, thus contributing to the bracing against lateral distortion. However, this feature is not essential and may be dispensed with.

All views of the accompanying drawing are made to a scale of two-thirds actual size from an actual commercial specimen of the tool.

Having thus described our invention, what we claim as new and desire to secure by Letters Patent is:

70 1. A spring compressing tool comprising a main lever member having a jaw portion and a handle portion, a jaw member, an actuating lever member extending through said jaw member and pivotally connected to said main lever member, and a pair of cross levers crossing said actuating lever and being respectively disposed

substantially in sliding contact therewith on opposite sides thereof and pivotally connected therewith, said cross levers being pivotally connected to said jaw member and slidably pivotally connected to the said main lever member, 80 and the said jaw member and actuating lever having cooperating engaging surfaces whereby the jaws of said main lever and of said jaw member will be maintained substantially parallel throughout the range of relative movement between said main lever and said actuating lever, in combination with a bifurcated locking member having a rearwardly extending release lever disposed between the planes of the sides of the said handles in all relative positions of said 90 handles, and a bifurcated U-shape wire spring having its loop extending through said release lever and with its furcations straddling and gripping the actuating lever and bearing against the handle secured thereto to force said release lever to locking position, said locking member having a bifurcated portion straddling said actuating lever and having its furcations respectively located between the sides of said actuating lever and the opposed faces of said jaw member and 100 having the forward end edges of said furcations formed with a plurality of stop faces to engage the rear edge of said jaw member.

2. A spring compressing tool comprising a main lever member having a jaw portion and a handle portion, a jaw member, an actuating lever member extending through said jaw member and pivotally connected at its forward end portion to said main lever member to the rear of the jaw thereof, and means connected to said 110 actuating lever for maintaining the jaws of said main lever and said jaw member substantially parallel throughout the range of their relative movement, in combination with a locking member having a rearwardly extending release lever disposed between said handles, and resilient means to force said locking member to operative position, said locking member having a bifurcated portion straddling said actuating lever and having its furcations respectively located 120 between the sides of said actuating lever and the opposed faces of said jaw member and having the forward end edges of said furcations formed with a plurality of stop faces to engage the rear edge of said jaw member.

3. A spring compressing tool comprising a main lever member having a jaw portion and a handle portion, a jaw member, an actuating lever member extending through said jaw member and pivotally connected to said main lever member and self compensating means connecting said jaw member and said main lever member to maintain their jaws in substantially parallel relation throughout their range of movement, in combination with a locking member having a rearwardly extending release lever disposed between said handles in all relative positions of said handles, and a spring to force said release lever to locking position, said locking member having a portion located between the 130 side of said actuating lever and the opposed face of said jaw member and having the forward end edge of said portion formed with a plurality of stop faces to engage the rear edge of said jaw member.

4. A spring compressing tool comprising a main lever member having a jaw portion and a handle portion, a jaw member and an actuating lever member extending through said jaw member and pivotally connected to said main 140 member

lever member, in combination with a locking member having a rearwardly extending release lever disposed between the planes of the sides of the said handles in all relative positions of said handles, and resilient means to force said release lever to locking position, said locking member having a bifurcated portion straddling said actuating lever and having its furcations respectively located between the sides of said actuating lever and the opposed faces of said jaw member and having the forward end edges of said furcations formed with a plurality of stop faces to engage the rear edge of said jaw member.

15. 5. A spring compressing tool comprising a main lever member having a jaw portion and

a handle portion, a jaw member, and an actuating lever member extending through said jaw member and pivotally connected at its forward end portion to said main lever member, in combination with a locking member having a rearwardly extending release lever disposed between the said handles in all relative positions of said handles, and resilient means to force said release lever to locking position, said locking member having a portion located between the side of said actuating lever and the opposed face of said jaw member and being formed with a stop face to engage the rear edge of said jaw member.
